(57) CLAIM

The ornamental design for a “dispenser,” as shown and described.

DESCRIPTION

FIG. 1 is a top perspective view of a first embodiment of “dispenser”, showing my new design;

FIG. 2 is a bottom perspective view thereof;

FIG. 3 is a top plan view thereof;

FIG. 4 is a right and left side elevation view thereof;

FIG. 6 is an enlarged front elevation view thereof;

FIG. 7 is an enlarged rear elevation view thereof;

FIG. 8 is a top perspective view of a second embodiment of the “dispenser” showing my new design;

FIG. 9 is a bottom perspective view thereof;

FIG. 10 is a top plan view thereof;

FIG. 11 is a bottom plan view thereof;

FIG. 12 is a right and left side elevation view thereof;

FIG. 13 is an enlarged front elevation view thereof; and,

FIG. 14 is an enlarged rear elevation view thereof.

The broken lines disclosed in the second embodiment (shown in full lines in the first embodiment) are for illustrative purposes only and form no part of this embodiment.
